UNITED STATES PATENT OFFICE.

CHARLES SUTTER, OF PITTSBURGH, PENNSYLVANIA.

ATTACHMENT FOR MAIL-BAG CATCHERS.

1,192,241.

Specification of Letters Patent. Patented July 25, 1916.

Application filed February 2, 1916. Serial No. 75,714.

To all whom it may concern:

Be it known that I, CHARLES SUTTER, a citizen of the United States, residing at Pittsburgh, in the county of Allegheny and 5 State of Pennsylvania, have invented certain new and useful Improvements in Attachments for Mail-Bag Catchers, of which the following is a specification.

This invention relates to an attachment 10 for mail bag catchers and has for its object to provide, in a manner as hereinafter set forth, means for forcing the bag into the crook of a catcher arm and for further maintaining the bag in such position under 15 such conditions overcoming the dropping of the bag from the catcher when the bag is not caught properly.

Further objects of the invention are to provide an attachment for mail bag catchers 20 for the purpose set forth which is simple in its construction and arrangement, strong, durable, efficient and convenient in its use, readily set up, and inexpensive.

With the foregoing and other objects in 25 view the invention consists of the novel construction, combination and arrangement of parts as hereinafter more specifically described and illustrated in the accompanying drawing, wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—Figure 1 is a top plan view of a mail bag catcher showing the adaptation therewith of an attachment in accordance with this invention, the 40 attachment being shown in full and dotted lines. Fig. 2 is a detail, broken away, and Fig. 3 is a detail.

Referring to the drawings in detail 1 denotes a supporting rod provided with a 45 series of diagonally disposed spaced angle-shaped notches 2, the forward wall of each being perpendicular and the rear wall beveled, as at 15, 16, respectively. The rod 1 is fixed to the side of a mail car, as well 50 as extending across the door-way thereof. 3 denotes a sleeve loosely mounted upon the rod 1 and which has attached thereto a handle 4. Carried by the sleeve 3 is a curved bracket 5 to which is connected the crook 6. 55 of a bag catcher arm 7. The foregoing elements constitute the form of mail bag

catcher now in general use, with this exception, that the rod 1 is not provided with the notches 2; these latter associate with the attachment to be presently referred to. 60

The arm 7 has an offset 8 near the crook 6 thereof and pivotally mounted thereon, as at 9, is a plate 10 having projecting therefrom a shifting arm 11 and a pusher arm 12, the latter being provided with a handle 65 13 and an offset 14.

The arm 11 is disposed at an angle with respect to the arm 12 and when the attachment is in normal position the arm 12 is arranged upon the arm 7 and the arm 11 extends across the space formed between the arm 7 and the rod 1 and said arm 11 is furthermore, when in normal position, arranged in close proximity to the mouth of the crook 6. 75

It will be assumed that the catcher is about to grab a bag and as the bag swings therein it engages the arm 11 causing the plate 10 to swing upon the pivot 9 and as the plate 10 swings the arm 12 will be shifted across the space between the arm 7 and rod 1 and the offset 14 will engage the bag, and on a further shifting of the plate 10, the arm 12 will push the bag into the crook 6 causing the bag to be securely held by the 80 catcher. The arm 12 when it is shifted by the plate 10 will ride over the notches 2 in the rod 1 until the arm 12 has reached the limit of its movement, the beveled walls of the notches permitting of such movement. 85 In case the arm 12 swings in an opposite direction, after it has pushed the bag, it will seat in a notch and the forward wall of the latter will lock the arm. 90

When the catcher is swung for the purpose of releasing the bag therefrom the arm 12 will move out of the notch and the attachment will be swung to normal position as indicated in full lines in Fig. 1 and the bag can be readily removed from the 100 catcher. 95

What I claim is:—

1. An attachment for mail bag catchers comprising the combination with a catcher including a horizontally disposed supporting rod and a permanently inclined catcher arm having its rear end formed with a substantially U-shaped crook pivotally connected with said rod, said arm having an outwardly projecting offset in advance of and in close proximity to said crook, of a shiftable plate pivotally mounted on said offset, 105 110

a shifting arm integral with said plate forwardly of the crook and normally extending in a direction toward and at an angle with respect to said rod, said shifting arm having its free end seating on said rod whereby the space between the latter and catcher arm is bridged, a forwardly extending pusher arm integral with the plate and normally superposed on said catcher arm forwardly of the crook and inclined to correspond to the inclination of said catcher arm, and said rod having spaced diagonally disposed notches any one of which is capable of receiving said pusher arm to lock it after being shifted in a rearward direction from normal position by the impact of a mail bag against said shifting arm.

2. An attachment for mail bag catchers comprising the combination with a catcher including a horizontally disposed supporting rod and a permanently inclined catcher arm having its rear end formed with a substantially U-shaped crook pivotally connected with said rod, said arm having an outwardly projecting offset in advance of and in close proximity to said crook, of a shiftable plate pivotally mounted on said offset, a shifting arm integral with said plate forwardly of the crook and normally extending in a direction toward and at an angle with respect to said rod, a forwardly extending pusher arm integral with the plate and normally extending forwardly and superposed on said catcher arm forward of the crook and inclined to correspond to the inclination of said catcher arm, and said rod having spaced diagonally disposed notches any one of which is capable of receiving said pusher arm to lock it after being shifted in a rearward direction by the impact of a mail bag against said shifting arm, said pusher arm having its forward arm provided with a handle offset with respect to the catcher arm.

3. An attachment for mail bag catchers comprising the combination with a catcher including a horizontally disposed supporting rod and a permanently inclined catcher arm having its rear end formed with a substantially U-shaped crook pivotally connected with said rod, said arm having an outwardly projecting offset in advance of and in close proximity to said crook, of a shiftable plate pivotally mounted on said offset, a shifting arm integral with said plate for-

wardly of the crook and normally extending in a direction toward and at an angle with respect to said rod, said shifting arm having its free end seating on said rod whereby the space between the latter and catcher arm is bridged, a forwardly extending pusher arm integral with the plate and normally superposed on said catcher arm forwardly of the crook and inclined to correspond to the inclination of said catcher arm, and said rod having spaced diagonally disposed notches any one of which is capable of receiving said pusher arm to lock it after being shifted in a rearward direction from normal position by the impact of a mail bag against said shifting arm, said pusher arm having the inner side near the rear end thereof provided with an elongated lateral offset normally extending toward said rod.

4. An attachment for mail bag catchers comprising the combination with a catcher including a horizontally disposed supporting rod and a permanently inclined catcher arm having its rear end formed with a substantially U-shaped crook pivotally connected with said rod, said arm having an outwardly projecting offset in advance of and in close proximity to said crook, of a shiftable plate pivotally mounted on said offset, a shifting arm integral with said plate forwardly of the crook and normally extending in a direction toward and at an angle with respect to said rod, a forwardly extending pusher arm integral with the plate and normally extending forwardly and superposed on said catcher arm forward of the crook and inclined to correspond to the inclination of said catcher arm, and said rod having spaced diagonally disposed notches any one of which is capable of receiving said pusher arm to lock it after being shifted in a rearward direction by the impact of a mail bag against said shifting arm, said pusher arm having its forward arm provided with a handle offset with respect to the catcher arm, and said pusher arm further provided on its inner side near its rear end with an elongated lateral offset normally extending toward said rod.

In testimony whereof I affix my signature in the presence of two witnesses.

CHARLES SUTTER.
